UNITED STATES PATENT OFFICE.

ALEXANDER R. CLARK, OF PETOSKEY, MICHIGAN.

DAMPER AND FLUE-VENTILATOR.

No. 926,174.

Specification of Letters Patent.

Patented June 29, 1909.

Application filed March 8, 1909. Serial No. 482,035.

To all whom it may concern:

Be it known that I, ALEXANDER R. CLARK, a citizen of the United States, residing at Petoskey, in the county of Emmet and State 5 of Michigan, have invented a new and useful Damper and Flue-Ventilator, of which the following is a specification.

The objects of the invention are, generally, the provision in a merchantable form of a device 10 of the class above specified which shall be inexpensive to manufacture, simple in operation and devoid of complicated parts; specifically, the provision of novel means for introducing a supply of cold air to the smoke pipe of a fuel receptacle, and of novel means 15 for controlling the influx of cool air; other and further objects being made manifest hereinafter as the description of the invention progresses.

20 The invention consists in the novel construction and arrangement of parts herein-after described, delineated in the accompanying drawings and particularly pointed out in that portion of this instrument wherein 25 patentable novelty is claimed for the distinctive and peculiar features of the device, it being understood that within the scope of what hereinafter is thus claimed, divers changes in the form, proportions, size and 30 minor details of construction may be made without departing from the spirit or sacrificing any of the advantages of the invention.

Similar numerals of reference are employed to denote corresponding parts 35 throughout the several figures of the drawings.

In the accompanying drawings, Figure 1 shows my invention in side elevation; Fig. 2 is a top plan of the damper; Fig. 3 is a vertical longitudinal section through the lateral pipe 5 shown in Fig. 1 the damper being cut transversely; Fig. 4 is a detail perspective of the collar; and, Fig. 5 is a detail perspective of the spindle upon which the damper is 45 mounted.

In the accompanying drawings, I have shown a fuel container which in the present instance takes the form of an ordinary stove, provided in its base with a draft aperture to 50 admit air below the grate, and with means for closing the aperture. Any of the common and well known devices adapted to the end sought may be used and I deem my description sufficiently clear if the position of 55 the aperture and its closing means be indicated generally by the numeral 2. The

stove, which may be adapted for a fuel of any sort, is provided with the usual stoke door 3, and from the rear of the device rises the smoke pipe 4.

60 The smoke pipe 4 is tapped, and from it projects a lateral air supply pipe 5 provided at its outer end with a removable plug 6. From the outer end of the pipe 5, a flue 7 extends downward, its lower end being open 65 and in close relation with the floor, the lower end of the flue 7 being supported by legs 8. A closing damper 9 is interposed in the portion 5.

70 Large latitude is desired in the arrangement and construction of the parts herein-before described. The stove may be replaced by a domestic heating furnace, or by a furnace of the type used in connection with steam-boilers, distilling plants and the like, 75 and the form of the piping will be varied to meet the exigencies of the particular case, bearing in mind the fact that at some points in the exit for the products of combustion, and preferably adjacent to the receptacle 80 into which the fuel is consumed, a duct having a suitable closure, is provided, whereby large quantities of cold air may be admitted to the exit for the combustion products.

To adhere, for the purpose of specific illustration, to the particular form of apparatus shown, the stove 1 may be filled with fuel and a fire lighted therein, the direct draft 2 being open and the damper 9 being closed. When the fire is thoroughly kindled, the 90 direct draft 2 may be closed and the damper 9 opened. The draft will then pass through the pipe section 5 and through the smoke pipe 4. The advantages of this operation are several. In the case of the particular 95 form shown, cold air will be drawn through the flue 7, and the floor and the lower atmosphere of the apartment kept warm, the apartment being ventilated at the same time. With the direct draft 2 closed and 100 the damper 9 opened, there will be no appreciable draft through the fuel container. The smoke and fuel particles will be thoroughly and effectively consumed instead of being drawn upward into the smoke flue, the 105 efficiency of the fuel being greatly increased in the case of the present invention.

With the direct draft 2 closed and the damper 9 open, the fire may be held for a long time, and when it is desired to start the fire anew, 110 the direct draft 2 may be opened and the damper 9 closed, whereupon the fire will in a

short time spring into activity. Another advantage of the device lies in the fact that, by admitting a supply of cold air into the smoke pipe 4, the formation of creosote in the pipe will be prevented, since this creosote formation takes place to best advantage in a rarefied atmosphere or in a closed receptacle, such as the smoke pipe of a stove. It is to be understood that the device need not be operated with the damper 9 entirely closed and with the direct draft 2 entirely open, or with the damper 9 entirely open and the direct draft 2 entirely closed. These parts may be so adjusted with respect to each other as to obtain any desired admixture in the smoke pipe 4. Now since the operation of a device of the character described depends upon the construction and operation of the element 9, I have given to this member 9, particular attention in the design of the apparatus, with a view to effecting, when desired, a complete and air tight closure of the pipe section 5.

Referring now particularly to Figs. 2 and 3 it will be seen that the damper 9 comprises a pair of flat plates 10 and 11 between which is mounted a sheet of flexible refractory material 12, preferably asbestos, the plates 10 and 11 and the member 12 being assembled by means of rivets 14. The plate 11 is transversely slotted in its diameter as will be noted by the numeral 15. The material which stands at the ends of this slot 15 in the diameter of the plate, is bulged to form trough shaped sockets 16 and 17. The trough shaped socket 17 at its outer end, is caused to flare to form a bell shaped bearing member 18 adapted to bear upon the inner surface of the stove pipe. The side walls of the member 17 in the end thereof which is remote from the bell shaped member 18, are slotted as denoted by the numeral 19. The sockets 16 and 17 are adapted to receive a spindle 20 whereby the damper is operated, the said spindle being provided at one end with the usual thumb piece 21. A collar 22 is slidably mounted upon the spindle 20 and a coiled spring 28 having one of its ends in abutment with the thumb-piece 21, serves to actuate the collar 22 toward the wall of the stove pipe to retain the damper in its place. Referring now particularly to Fig. 4, it will be seen that the collar 22 is pierced by two slots 23 and 24 disposed at right angles to each other, the slot 24 being somewhat shorter than the slot 23.

Referring to Fig. 5, it will be seen that the spindle 20 is provided with diametrically opposite, upstanding lugs 25 each terminating at one end in an enlarged head 26. Beyond the lugs 25 is another pair of outstanding lugs 27.

The method of assembling the damper is as follows:—The spindle 20 is inserted into the collar 22, the lugs 25, and the heads 26

pass freely through the slot 23, the spring 28 being compressed in the operation. When the collar 22 has passed the lugs 25, the said collar is given a partial rotation, to bring the slot 24 of the collar 22 into alignment with the lugs 25. These lugs 25 are arranged to traverse the slots 24 in the collar and when the collar is released the spring 28 will cause the said lugs 25 to move in the slot 24 as aforesaid. The heads 26, however, cannot pass through the slot 24 and the collar 22 will therefore remain assembled with the spindle 20. The damper 9 is then introduced within the stove-pipe, and the spindle 20 is passed through an aperture in the pipe 80 and into the socket 17. It will be seen by referring to Fig. 3, that the distance between the wall of the socket and the asbestos member 12 is sufficient to allow the lugs 27 when disposed at right angles to the damper, to pass between the wall of the socket 17 and the member 12 and that the space between the walls of the socket 17 itself, is not sufficient to allow the passage of the lugs 27 between them except when as hereinbefore described, the said lugs 27 are disposed parallel to the walls of the socket 17 and at right angles to the damper proper. The spindle 20 therefore is passed into the socket 17 with the lugs 27 disposed at right angles to the damper and after the section 27 has passed beyond the end of the socket 17 the spindle 20 is turned through an angle of 45° and released whereupon the tension of the spring 28 will cause the lugs 27 to move backward engaging the slots 19 in the walls of the socket 17, securing the damper to the spindle and both the damper and the spindle in position upon the pipe. Now while the spindle has thus been engaging the socket 17, the extremity 29 of the spindle will have passed into the socket 16. It has been stated hereinbefore that these sockets 16 and 17 were trough shaped, that is, that they were open toward the member 12 which is disposed between the plates 10 and 11. This being the case, it is obvious that with the construction hereinbefore pointed out in the extremity 29 of the spindle would be likely to move in the socket 16, coming in contact with the asbestos member 12 to the damage of the same. In order to obviate this difficulty, a portion of the plate 11 adjacent the slot 15 therein is bent outward from each side of the said slot to form a seat to receive the spindle 20, as best shown in Fig. 3. The ends of these portions which in Figs. 2 and 3 are designated by the numeral 30 are carried through the member 12 and through the plate 10, their extremities being over-bent and clenched upon the plate 10, as shown in Fig. 3. The disposition of these ends 30 serves not only to maintain the spindle 3 from contact with the member 12 and to hold the said spindle rigidly in place, but at the same time serves

to aid the rivets 14 in firmly assembling the parts of the device.

As hereinbefore pointed out, the member 12 is allowed to extend peripherally beyond the plates 10 and 11 to form a yieldable edge, and as denoted by the numeral 31 in Fig. 3 the pipe in which the damper is mounted is contracted to engage the periphery of the damper.

10 It will be seen that by means of the arrangement last above described, it is possible to control absolutely the influx of cold air through the supply pipe 5, and furthermore, since the yieldable pipe engaging periphery of the damper is fashioned from asbestos or like material, the said damper is not likely to become burned out or damaged, even if the pipe should become heated to a high degree.

15 20 The foregoing mechanism although simple in construction is well adapted to control with precision the influx of cold air into a smoke pipe, or flue, in a device of the class described.

25 Having thus described my invention what I claim as new and desire to protect by Letters Patent is.

30 1. In a device of the class described, a damper comprising a pair of metallic plates, and a refractory member interposed between the plates and rigidly assembled therewith, the refractory member being ex-

tended laterally beyond the plates to provide a yieldable, pipe engaging edge.

2. In a device of the class described, a 35 damper comprising a pair of metallic plates, and a refractory member interposed between the plates, the refractory member being extended laterally beyond the plates to present a yieldable pipe engaging edge; one 40 of said plates being slotted, a portion of said plate at the edge of the slot being bent to pierce the refractory member to engage the other plate.

3. In a device of the class described, a 45 damper comprising a pair of metallic plates, a refractory member interposed between the plates, one of said plates being bulged in its diameter adjacent its edges to form sockets, the said plate being slotted between the 50 sockets; a spindle for rotating the damper mounted in the sockets; the walls of the slotted plate adjacent the slot, being outbent to form a seat to receive the spindle, and being carried terminally through the refractory member and through the other plate, and being clenched upon the other plate.

In testimony that I claim the foregoing as my own, I have hereto affixed my signature in the presence of two witnesses.
